Primary Examiner — Daniel Bui*Assistant Examiner* — Khawaja Anwar(74) *Attorney, Agent, or Firm* — Justin M Tromp(57) **CLAIM**

The ornamental design for a laser printer toner cartridge, as shown and described.

DESCRIPTION

FIG. 1 is a front, right side perspective view of a laser printer toner cartridge, showing our new design;

FIG. 2 is a rear, left side perspective view thereof;

FIG. 3 is a front, right side perspective view thereof;

FIG. 4 is a front elevation view thereof;

FIG. 5 is a right side elevation view thereof;

FIG. 6 is a rear elevation view thereof;

FIG. 7 is a left side elevation view thereof;

FIG. 8 is a top plan view thereof; and,

FIG. 9 is a bottom plan view thereof.

The features shown in broken lines depict environmental subject matter only and form no part of the claimed design.
